UNITED STATES PATENT OFFICE

112,047

DESIGN FOR A BEDSPRING

Edward W. Schlappritz, Minneapolis, Minn.

Application November 8, 1937, Serial No. 72,707

Term of patent 14 years

To all whom it may concern:

Be it known that I, Edward W. Schlappritz, a citizen of the United States of America, residing at Minneapolis, in the county of Hennepin and State of Minnesota, have invented a new, original, and ornamental Design for a Bedspring, of which the following is a specification, reference being had therein to the accompanying drawing forming a part thereof, wherein:

The figure is a perspective view of the bedspring, showing my design.

I claim:

The ornamental design for a bedspring, substantially as shown.

EDWARD W. SCHLAPPITZI.
